DISCHARGING GAP DEVICE FOR A MAGNETIC BLOW-OUT ARRESTER

The present invention relates to a discharging gap device for a magnetic blowout arrester in which the dynamic current is blown into a narrow chamber to raise the arc voltage so as to throttle and cut off the dynamic current.

Generally, arresters of the prior art rely on magnetic manipulation for blowing the dynamic current into a narrow arc extinguishing chamber to raise the arc voltage, thereby throttling the dynamic current and increasing the chopping efficiency. To attain the end, the arresters require a magnetic field of very high intensity for manipulating the arc. This makes it necessary to increase the number of turns of the blowout coil built into the arresters, which in turn makes it necessary to provide means to raise the arc voltage in the protective gap of the blowout coil so that the dynamic current may be branched off as much as possible to the blowout coil. Moreover, the voltage which the blowout coil can withstand (mainly the impact voltage) must be increased. These problems are hard to overcome.

It has hitherto been customary to provide, in an arc extinguishing chamber, a pair of discharge electrodes for forming a discharging gap or a guide electrode for aiding in the movement of the arc. In both of these cases, the length of the arc can be increased if the length of the electrode or electrodes is reduced, but a magnetic field of very high intensity is required for arc manipulation.

This invention has as its object the provision of a discharging gap device for a magnetic blowout arrester which permits to provide a magnetic field of very high intensity, reduce the number of turns of the blowout coil and reduce the diameter of the chamber.

FIGS. 1a and 1b are plan views of electrode arrangements of prior art devices;

FIG. 2 is an exploded perspective view of a discharging gap device according to this invention;

FIG. 3 is a connection diagram of the discharging gap device according to this invention;

FIG. 4 is a longitudinal sectional view of the arc extinguishing chamber used in the present invention; and

FIGS. 5 to 7 are perspective views showing parts used in the present invention, FIG. 5 showing the guide electrode, FIG. 6 a discharge electrode and FIG. 7 a rivet for fixing the electrode.

Before describing an embodiment of this invention with reference to the drawings, prior art devices will be described with reference to FIG. 1 to enable the object, construction and operation of the present invention to be understood more clearly.

FIG. 1a shows a pair of discharge electrodes 2, 2 mounted in an arc extinguishing chamber 1 to provide a discharging gap therein. FIG. 1b additionally shows a guide electrode 3 mounted for aiding in the movement of the arc. In both examples shown, if a magnetic field is applied to the chamber 1 from outside in a direction perpendicular to the plane of the FIG., a magnetic field produced by a current passed through the electrodes 2, 2 will be added to the externally applied magnetic field, so that the density of the magnetic field is increased in an area surrounded by the electrodes 2, 2 and the arc as indicated by dots. The pressure exerted by the magnetic field causes the arc to move toward the outer periphery as indicated by arrows. Thus, to increase the dynamic current chopping efficiency requires to extend the arc more rapidly and to a greater length even when the external magnetic field is low in intensity. The results of tests have shown that in the case of the electrode arrangement of FIG. 1a, the greater the length of the electrodes 2, 2, the more rapid is the movement of the arc. Generally, however, the larger the electrodes, the smaller is the length of the arc that can be produced when the diameter of the chamber is constant. The results are more or less the same with the arrangement of FIG. 1b. Thus, if the length of the electrodes 2, 2 is reduced, it is possible to increase the length of the arc in the electrode arrangements shown in FIGS. 1a and 1b but a magnetic field of very high intensity must be provided for arc manipulation.

The present invention has been made with a view to providing a magnetic field of very high intensity, reducing the number of turns of the blowout coil and reducing the diameter of the arc extinguishing chamber. An embodiment of the invention will be described with reference to the drawings.

FIG. 2 shows a shallow, cylindrical wall 1 of an arc extinguishing chamber. The wall 1 consists of heat resisting insulating material and is integral with an axially central partition plate 11. The plate has a central tubular portion 14 about an axial bore 12, and an outer, substantially annular portion 13 which axially tapers from its circumference toward the tubular portion 14. Recesses 15 in the two opposite faces of the plate portion 13 respectively accommodate elongated discharge electrodes 2. A radial groove 16 in each face leads outward to an opening in the chamber wall 1 remote from the corresponding electrode 2, the two grooves being diametrically opposite each other. A radial slot 17 in the plate portion 13 extends from the tubular portion 14 to the chamber wall 1 and connects the two sections of the chamber otherwise separated by the plate 11. The plate portion 13 has axial openings 18 spacedly adjacent the slot 17.

The discharge electrodes 2, 2 are semicircular in shape as shown in FIG. 6 and are mounted on the upper surface and lower surface respectively of the partition plate 11 in such a manner that their convex sides are directed toward the portion 14, and the slot 17 is disposed circumferentially between the electrodes which are fixed by tubular rivets 4 (FIG. 7) sealed in the openings 18. A rod-shaped guide electrode 3 has a helical, central portion of one and one-half turns coiled about the tubular partition plate portion 14 and passing through the slot 17. The straight radial ends of the electrode 3 are received in the grooves 16 respectively.

In the assembled condition of the device, the bore 12 receives a spring 5 between two cylindrical metal plugs 6 smaller in diameter than the bore. The plugs are held in place by two flat, circular covers 7 of heat-resisting insulating material which close the axial ends of the chamber and whose outer faces carry electrode plates 8. The electrode plates 8 are connected in the assembled device by nonillustrated conductors passing through openings in the covers 7 aligned with the rivets 4.

Each of the plugs 6 and the associate electrode plate 8 constitute a capacitor, and corona discharge takes place between the plugs 6 and the covers 7 immediately before the occurrence of discharge.

The capacitors improve the distribution of electric potentials when several discharging gaps are provided. Corona discharge exerts favorable influences on the operation of the device when an impact discharge voltage is applied thereto. In FIG. 3, L designates a blowout coil, gl a protective gap, and R a dynamic current limiting resistor.

The operation of the device constructed as aforementioned according to this invention will now be explained. Upon application of an impact voltage to the arrester, discharge takes place between the discharge electrodes 2, 2 and the adjacent upper and lower portions of the guide electrode 3. A dynamic current which flows following the occurrence of discharge is passed through the protective gap gl and blowout coil L to produce a magnetic field in the coil L. Discharge first takes place between the substantially central portion of each arcuate discharge electrode 2 and the guide electrode 3, said central portion being disposed nearest to the guide electrode of all the portions of each discharge electrode. Then discharge takes place between the two discharge electrodes 2 through the intermediary of the guide electrode 3. If an arc is formed, a current caused by the arc and a current passed through the guide electrode 3 flow in opposite directions and are disposed in close proximity to each other as shown by arrows in FIG. 2. Thus, magnetic fields are formed by the oppositely directed currents in an area closed by the dynamic current. Moreover, the magnetic field produced in the blowout coil L is also applied to said area so that the magnetic field in said portion becomes very dense. This causes the arc to be pulled rapidly and with a great force toward the periphery of the chamber

and, at the same time, the arc is cooled by the portion 13 and the impedance is increased. Combined with the action of the resistor R, this chops the dynamic current. Particularly, if the distance e between the arc current and the guide electrode 3 is reduced, it is possible to boost the chopping effect on the dynamic current. The gas produced after the chopping of the dynamic current is discharged through the grooves 16 to the outside. It will be readily understood that the device constructed as aforementioned offers substantial advantages.

First, the invention permits to reduce the number of turns of the blowout coil L. If the device of the invention is intended for chopping the current without boosting the arc voltage, the blowout coil L can be eliminated entirely.

Secondly, the arc formed between the discharge electrodes moves along substantially one half the circumference of the arc extinguishing chamber as shown by a solid line in its upper section and then passes through the guide electrode 3 to the lower section of the chamber where it moves along substantially one half the circumference of the chamber as shown by a broken line, so that the arc is greatly lengthened and the diameter of the chamber 1 can be greatly reduced.

It is to be understood that the invention is not limited to the specific embodiment shown and described herein, and that many changes and modifications may be made therein without departing from the spirit of the invention which is defined in the appended claims.

We claim:

1. A discharging gap device comprising, in combination:
  - a. wall means of heat-resisting insulating material defining a chamber;
  - b. a partition element of said material dividing said chamber into two sections communicating through an opening in said element;
  - c. a guide electrode extending through said opening and

having respective portions in said sections;

- d. respective discharge electrodes spacedly juxtaposed in said sections to said portions; and
- e. two conductors on said wall means outside said chamber and respectively connected to said discharge electrodes.

5 5. A device as set forth in claim 1, wherein each discharge electrode and the associated portion of said guide electrode constitute a pair of gap-defining members, respective parts of said members being closest adjacent each other, the spacing of said members increasing in a direction away from said parts.

6 6. A device as set forth in claim 2, wherein said portions of said guide electrode are substantially helically arcuate about an axis, and said discharge electrodes are spaced from the associated portions of the guide electrode in a direction away

15 from said axis.

7 7. A device as set forth in claim 3, wherein said discharge electrodes are arcuate and have each a convex face opposite the associated portions of said guide electrode.

8 8. A device as set forth in claim 3, wherein said wall means

20 include two covers of said material axially closing said chamber, and carrying said conductors, said partition element having a tubular central portion about said axis, two conductively connected metallic members received in said tubular portion in abutting engagement with said covers respectively, each metallic member and a corresponding one of said conductors jointly constituting a capacitor, one of said covers being interposed between each metallic member and the corresponding conductor.

9 9. A device as set forth in claim 5, wherein said wall means

30 substantially close said chamber, the axial height of each

section between said element and a respective cover

decreasing in a direction from said guide electrode away from

said axis.
